CLAIM

The ornamental design for a combined holder and organizer for thread or the like, as shown and described.

DESCRIPTION

FIG. 1 is a front elevational view of a combined holder and organizer for thread or the like, showing our new design.

FIG. 2 is a top plan view thereof.

FIG. 3 is a side elevational view thereof.

FIG. 4 is a sectional view taken on the line 4—4 of FIG. 1.

FIG. 5 is a bottom plan view.
